UNITED STATES PATENT OFFICE.

WALTER S. MAYER, OF PHILADELPHIA, PENNSYLVANIA, ASSIGNOR TO HEINEMANN ELECTRIC COMPANY, OF PHILADELPHIA, PENNSYLVANIA, A CORPORATION OF PENNSYLVANIA.

ELECTRIC SWITCH.

Application filed July 22, 1921. Serial No. 486,710.

To all whom it may concern:

Be it known that I, WALTER S. MAYER, a citizen of the United States, residing in the city of Philadelphia, county of Philadelphia, and State of Pennsylvania, have invented certain Improvements in Electric Switches, of which the following is a specification.

This invention is an electric switch characterized, in its preferred construction, by the combination with a case, of an oscillatory plural pole make and break mechanism provided with fuses that can be replaced in the open position of the switch without opening the case and with means for effecting automatically the quick throw of the switch in making and breaking the circuit.

The improvements provide the desiderata of an externally operated quick throw switch having fuses that can be replaced while the contacts are in the open relation and fully enclosed contacts that are "dead" when the switch is in the open position, safety in both the open and closed positions, and immateriality as to how the line and load connections are made.

The improvements are embodied in the mechanism set out in the following description and the accompanying drawings in illustration thereof.

In the drawings, Fig. 1 is a top plan view of the encased switch; Fig. 2 is a sectional view taken on the line 2^x—2^x of Fig. 1, in the open position of the switch; Fig. 3 is a sectional view taken on the line 3^x—3^x of Figs. 1 and 4, in the open position of the switch, and Fig. 4 is a sectional plan view taken through the switch in the closed position thereof.

The mechanism as illustrated in the drawing, comprises the metal case 1 having the lid 2 connected therewith by the hinges 3 and adapted to be fastened thereon by the registering eyes 1' and 2' adapted for engagement by a lock, the lid being provided with an arched dome 1" containing the rectangular aperture 1^a.

A base 4, of insulating material, is fixed within the case 1 to the bottom thereof, as by screws 5, and has fixed on opposite sides thereof the sets of electrical couplings 6, 7, 8, 9, and 6', 7', 8', 9', and by the respective binding screws 10, 11, 12, 13, and 10', 11', 12' and 13'. The couplings 7, 8, and 7', 8' have fixed thereto the respective contact jaws 14, 15,

and 14', 15', by the respective screws 16 and 16'.

Contact blades 17, 18, and 17', 18' are fixed to an insulating body 19 by respective conducting bearings 18" and 18'" which are electrically separated and clamped together, through the bottom of the insulating sockets 19' forming part of the body 19, by binding screws 20. Conducting shells 21 are set in the sockets 19' in contact with the respective parts 18'" and are engaged by the insulating disks 22 which are held in place by the washers 23 and the screw 20. Fuse plugs 24 are screwed into the shells 21, whereby the members 20 and 21 are electrically connected and connect the blade 17 with the blade 17' and 18 with 18' through the parts described.

The body 19 has set in its ends the bearings 25 which carry the trunnions 26. These trunnions are journalled in the bearings 27 fixed in the ends of the base 4. Studs 28 on the bearings 25 act in circular arcs 29 in the bearings 27 to limit the oscillatory movement of the block and hold the blades 17, 18, and 17', 18' in position for correct engagement with the respective jaws 14, 15, and 14', 15' to close the switch and to hold the block and blades at the limit of the desired movement in the open position of the switch.

A link 30 is provided with a slot 30' in which is connected a stud or pivot 28. The link is connected by a pivot 31 with a crank arm 32 fixed to a journal 33 adapted to rock in the bearing 34 carried by the case 1, the journal being rocked by a handle 35 fixed thereto exterior to the case.

A coiled spring 36 is disposed on the link 30 between the pivots 28 and 31, being compressed by the movement of the pivot 28 in the slot 30' until the dead center has been passed in operating the arm 32 to rock the body 19, the spring then acting to throw the body quickly in both the make and break operations.

A perforated bearing 29', fixed to an end of the case or housing 1, engages the handle 35 in the open position of the switch and provides means for the engagement of a lock to hold the handle thereto and the switch in the open position.

With the switch in the open position illustrated in Figs. 1, 2 and 3, the blades 17, 17', 18, 18' are disengaged from the respective jaws 14, 14', 15, 15', with which they are

adapted to engage in the closed position of the switch, as illustrated in Fig. 4. To close the switch, the handle 35 is turned from the position illustrated in Fig. 1 toward that illustrated in Fig. 4, the shaft 33 with the arm 32 fixed thereon being turned to the right from the position shown in Fig. 2 toward that shown in Fig. 4. Thereby the pivot 31 of the link 30 moves the latter longitudinally against the action of the spring 36 thereon and rocks it about the stud 28 as it moves in the slot 30' thereof, with the result that when the link between the centres of the parts 31 and 38 has passed to the right of the part 28 or past the "dead centre" position, the action of the compressed spring 36 on the stud 33 will throw the latter toward the outer end of the slot and rock the part 19 to which the stud is fixed through the part 25. This expansion of the spring after the passage of the dead centre position not only throws the stud 28 to the left, but also the stud 31 to the right, this movement for closing the switch being completed automatically, by a quick action, and the reverse movement for opening the switch being effected in a similar manner. In the closed position of the switch, the couplings 7 and 7' are electrically connected through the parts 14, 17, 17' and 14' and the corresponding plug 24 with its connections between the parts 17 and 17', and the couplings 8 and 8' are electrically connected through the parts 15, 18, 18' and 15' and the corresponding plug 24 with its connection between the parts 18 and 18'.

Having described my invention, I claim:

1. An electric switch comprising the combination with a case provided with an opening, a base provided with bearings in said case, and relatively insulated conducting contacts fixed to said base in said case, of a device journalled relatively to said bearings and adapted to oscillate in said case, insulated conducting contacts fixed to said device and adapted in different positions thereof to make and break a circuit through said contacts first named, means for effecting automatically a quick make and break between said contacts first and second named, and a fuse carried by said device for electrically connecting said contacts second named, said fuse adapted to register with said opening in the open position of said switch and to be out of registration with said opening in the closed position of said switch.

2. An electric switch comprising the combination with a case provided with a relatively movable lid having an opening therein, a base having bearings thereon and a plurality of sets of insulated contacts fixed to said base in said case, of a device journalled relatively to said bearings and adapted to oscillate in said case, a plurality of sets of insulated contacts fixed to said device and

adapted in different positions thereof to make and break electrical connections with the respective sets of contacts first named, means for effecting automatically a quick make and break between said contacts first and second named, and a plurality of fuses carried by said device for electrically connecting contacts of the respective sets second named, said fuses adapted to register with the opening of said lid in the closed position thereof and in the open position of said switch and said lid in the closed position thereof preventing the removal of said fuses in the closed position of said switch.

3. An electric switch comprising the combination with a case having a lid with an opening therein and insulated contacts fixed in said case, of a device provided with a fuse plug socket adapted to oscillate in said case, a fuse plug in said socket, contacts fixed to said device and connected through said plug to make and break a circuit through said contacts first named, said fuse plug being in registration with said opening in the open relation of said contacts and out of registration with said opening in the closed relation of said contacts, and automatically acting mechanism comprising an arm, an oscillatory slotted link having a spring controlled movable stud arranged to travel in said slot for effecting a quick make and break between said contacts.

4. An electric switch comprising a housing, an insulating base in said housing, contacts fixed to said base, an insulating oscillatory body having bearings mounted in said housing, mechanism comprising a crank journalled in said housing, a crank arm fixed thereto, an oscillating slotted link connected with said body and having a spring controlled movable stud arranged to travel in said slot, for oscillating said body, said mechanism comprising automatically acting means for effecting a quick throw, a fuse carried by said body, and contacts fixed to said body and electrically connected through said fuse, said contacts second named being adapted for making and breaking a circuit through said contacts first named.

5. A switch comprising the combination with a housing, an insulating base therein, and contacts fixed on said base, of an oscillatory insulating body, bearings for said body fixed on said base, a fuse plug connected detachably to said body, contacts fixed to said body and electrically connected through said plug, said contacts second named adapted to make and break a circuit through said contacts first named, means comprising a manually operated crank journalled in said housing and an oscillating slotted link having a spring controlled movable stud arranged to travel in said slot for oscillating said body, and means for engaging and fastening said crank to said

housing to hold said switch in the open position.

6. An electric switch comprising the combination of a case provided with an opening, an insulating base fixed in said case and having electrically separated conducting contacts fixed thereto, an insulating body having a convex periphery journaled in said case and provided with contacts adapted to be oscillated thereby to engage and disengage the contacts aforesaid, said body having one or more sockets adapted for holding a fuse or fuses for connecting the contacts carried thereby and being
- adapted for placing said fuse or fuses in registration with said opening in the open position of said switch and for closing said opening by said convex periphery with said fuse or fuses out of registration therewith in the closed position of said switch, and means for effecting automatically a quick movement of said body to effect a quick make and break between said movable and stationary contacts.

In testimony whereof I have hereunto set my name this 20 day of July, 1921.

WALTER S. MAYER.
